GUNS

Fernando Garcia Prieto, Los Angeles, Calif.

Application November 4, 1954, Serial No. 466,856

1 Claim. (Cl. 89—8)

The present invention relates to improvements in guns, and the primary object of the invention is to provide a gun in which the energy of a powder charge is better utilized than in conventional guns.

Another object of the invention is to provide a gun in which two or more powder charges are exploded to fire a projectile, one outside and other or others inside the barrel.

A further object of the invention is to provide a gun in which the conventional recoil is eliminated and the force producing said recoil is utilized to increase the efficiency of the gun.

The foregoing and other objects, features, and advantages of the invention will become more clearly evident from the following detailed description of an exemplary form of the invention, the same being illustrated in the accompanying drawing, in which:

Fig. 1 is a longitudinal sectional view of a gun embodying the present invention.

Fig. 2 is an enlarged sectional view showing a detail of the projectile used in said gun.

Figs. 3 and 4 are diagrams serving to illustrate the Pascal's principle on which the present invention is based.

The gun shown in Fig. 1 comprises a cylinder 5 open at both ends and provided with two groups of exhaust ports 6 and a powder port 7; a pair of pistons 8 and 9 arranged to slide within the cylinder 5 and forming an explosion chamber 10 between them; a casing 11 housing said cylinder; a barrel 12 forming a reduced extension of said casing; a three-throw crankshaft 13 affixed to said casing, one crank being connected to piston 9 by rod 9a and the other cranks being connected to piston 8 by rods 8a and 8b which are united at 8c; an inertia member 14 connected to both pistons 8 and 9 through said rods and crankshaft, said inertia member being adapted to slide within the rear portion of the barrel 12; a projectile 15 adapted to slide within the barrel 12, said projectile having a compartment 15a for receiving a powder charge.

The barrel 12 has a longitudinal slot 12a intermediate the length of said barrel. The outer end of said slot is defined by a shoulder 12b that serves to inwardly flex a spring 15b carried by the compartment 15a and movable along the slot 12a, said spring being provided with a prong 15c to hit a percussion cap 15d (Fig. 2).

The operation of the gun shown is as follows:

A powder charge is introduced in the explosion chamber 10 through the port 7, and said charge is ignited by conventional means (not shown). The resultant explosion urges both pistons 8 and 9 in opposite directions along the cylinder 5. Said pistons, through the above described connections, simultaneously urge the inertia member 14 along the portion of the barrel 12 that is adjacent to the casing 11 and, therefore, transmit their kinetic energy to the projectile 15 in contact with said inertia member. Just before the pistons 8 and 9 reach

2

their extreme outward positions, they uncover the exhaust ports 6 and the exhaust gases escape therethrough. The projectile 15 will move along the barrel 12, and, when the spring 15b reaches the shoulder 12b, said spring will flex inwardly to push its prong 15c into the cap 15d, thus exploding the powder charge in compartment 15a. The burnt gases remaining in the cylinder 5 may be scavenged by conventional means (not shown), and the port 7 may be open and the operation repeated.

Fig. 3 shows a cylinder open at one end and closed at the other end and provided with one piston. If an explosion is produced in the space between said piston and said closed end, a pressure, represented by arrow *a*, is exerted on said piston and another pressure, represented by arrow *b*, is exerted on the closed end *c*. In a conventional gun the pressure represented by arrow *a* is exerted on the projectile to impel it outward and the pressure represented by arrow *b* is exerted on the gun's breech producing recoil, or, if the cylinder is open at both ends, as in the so-called bazooka gun, the energy of said pressure is lost.

Fig. 4 shows a cylinder open at both ends and provided with two opposed pistons. If an explosion is produced in the space between said pistons, a pressure *a* is exerted on piston 8 and a pressure *b* on piston 9. According to Pascal's principle, both pressures are of equal intensity having equal maximum and equal minimum. If the charge exploded in the first cylinder is of the same force to that exploded in the latter cylinder, the average pressure on both cylinders will be equal. Consequently, pressure *a* and pressure *b* are of the same force in Fig. 4 and in Fig. 3.

The energy of a powder charge, therefore, will produce in my gun twice as much work as is produced in conventional guns, that is, the projectile of the gun disclosed in the present application will be fired with double energy than the projectile of conventional guns.

The explosion in chamber 10 exerts pressures of equal intensity in the pistons 8 and 9 and said pressures are simultaneously transmitted to the member 14 urging forward said member and propelling the projectile 15 in the same direction.

Since the pressure on each piston is equal to that exerted on the projectile of conventional guns, it will be evident that the impulse exerted on the projectile 15 will be twice as great to that exerted on the projectile of conventional guns, if the powder charge is of the same force in both cases.

Furthermore, the explosion in compartment 15a will produce an additional impulse on the projectile 15, thus increasing the velocity acquired by said projectile from the explosion in the chamber 10.

It will be also evident that the rotation of the crankshaft 13 will not affect the gun structure since the speed of every point in a rotating body is proportional to its distance from the center of rotation and, consequently, the center line of the crankshaft 13 will remain stationary and no recoil can be produced. Also, when the piston 9 pushes downward the crank of the crankshaft 13 connected to said piston, the piston 8, simultaneously pulls upward the cranks connected to the latter piston, and the forces acting on both pistons are counteracted by the force of inertia opposed to said motion, both action and reaction balancing each other.

Since variations of the present combination may be made within the concept of the invention, I wish to reserve to myself all modifications thereof that may fall within the scope of the pending claim.

I claim:

1. A gun comprising a casing, a cylinder inside said cas-

ing, a barrel forming an extension of said casing and adapted to house a projectile, a pair of opposed pistons operable in said cylinder and having an explosion chamber therebetween, an inertia member, and means connecting said member to said pistons, said member being positioned to be impelled by both pistons simultaneously and at the same degree and rate of movement into said barrel upon separation of said pistons by an explosive charge in said explosion chamber, and said projectile receiving the kinetic energy of said member to be impelled outward from said barrel.
